UNITED STATES PATENT OFFICE.

CHARLES N. FORREST, OF RAHWAY, HAROLD P. HAYDEN, OF RARITAN TOWNSHIP, MIDDLESEX COUNTY, NEW JERSEY, AND ORIN R. DOUTHETT, OF BEAVER FALLS, PENNSYLVANIA, ASSIGNEES TO THE BARBER ASPHALT COMPANY, OF PHILADELPHIA, PENNSYLVANIA, A CORPORATION OF WEST VIRGINIA.

GILSONITIC PRODUCT.

No Drawing. Original application filed August 28, 1919, Serial No. 320,514. Divided and this application filed April 3, 1922. Serial No. 549,187.

To all whom it may concern:

Be it known that we, CHARLES N. FORREST, of Rahway, in the county of Union and State of New Jersey, HAROLD P. HAYDEN, of Raritan Township, in the county of Middlesex and State of New Jersey, and ORIN R. DOUTHETT, of Beaver Falls, in the county of Beaver and State of Pennsylvania, citizens of the United States, have invented certain new and useful Improvements in Gilsonitic Products, whereof the following is a specification.

Our invention relates to gilsonitic products and their manufacture, and more especially to products and materials obtainable from gilsonite through sulphonation treatment. We have found that there can be obtained from gilsonite and gilsonitic substances certain products which exhibit various useful properties of true sulphonic substances.

This application is a division of our application, Serial No. 320,514, filed August 28, 1919, entitled "Gilsonitic products and their manufacture."

The various phases of our invention will be specifically described hereinafter in accordance with the best mode of applying them in a practical way at present known to us.

As a gilsonitic material to be treated, we ordinarily prefer gilsonite distillate to native gilsonite itself. We have obtained a much greater yield of sulphonie products from the treatment by preparing the distillate sometime in advance and allowing it to "age" for a considerable period before being treated. Such distillate may be prepared as follows:

Gilsonite as received from the mine is charged into an iron or steel still, fired with gas or oil (or otherwise suitably heated), and connected to a suitable condenser,—such as an iron pipe condenser water-cooled. Any convenient quantity of gilsonite may be charged,—say 600 pounds to several tons. The still being closed and heat applied gradually, the gilsonite will liquefy and collect in the bottom of the still, and vapor and gas evolving from it will fill the top of the still and pass over

into the condenser. As the heating progresses, temperature readings should be taken from time to time on the body of vapor in the upper portion of the still, as well as on the body of liquid beneath it. (Excepting as there may be special occasion for distinguishing them, we here and hereinafter comprehend mingled gases and vapors under the single term "vapor", for the sake of brevity. For convenience, we refer to various stages of operations by the corresponding vapor temperatures, unless otherwise specially noted.) The effect of the progressive heating of the gilsonite is to gradually break it up and decompose it chemically,—whence, mainly, the evolution of vapor. The coming off of vapor from the still begins at a temperature of some 165° F., and continues up to or even beyond coking temperatures.

Up to the point where the vapor temperature approaches some 550° F., the distillation may be carried out as rapidly as the contents of the still can be made to absorb heat. At this point, however, some exothermic or other peculiar action occurs, so that the evolution of vapor in the still tends to become excessively rapid. Unless, therefore, the previous heating has been especially slow, it is necessary to reduce the application of heating very greatly as this critical point is approached, in order that undistilled liquid may not be carried over into the condenser, and clog it up so as to render it unusable. In practice, it will usually be found convenient to cut down the fire some 100° F., in advance of this temperature. Once this critical point is well passed, the fire may be increased and the distillation pushed on as rapidly as desired to its conclusion. In practice, the heating need not be carried further than a temperature of some 850° F., measured on the solid coke product collecting in the bottom of the still.

While the vapor coming off from the still may all be led into the iron pipe condenser, as above suggested, and all of the strictly vaporous portion thereof there condensed and collected as a liquid, a slightly different procedure is preferable. A minor portion of the vapor is condensable at relatively

high temperatures; and at the temperatures in the condenser, the corresponding condensate is of such thick, gummy consistency that it would tend to clog it up. It is desirable, therefore, that this heavier portion of the normally liquid products be condensed and collected separately, without entering the condenser at all. This can advantageously be taken care of by making the pipe leading from the still to the condenser of substantial length and providing it with a trap. With this arrangement, the heavier portion of the normally liquid products will be condensed by the cooling effect of the atmosphere upon the pipe (which thus acts as a sort of auxiliary condenser), and will collect in the trap, whence it can be drawn off from time to time and added to the liquid products drawn from the condenser itself. The trap also affords a measure of protection against the effects of too rapid heating at the critical temperature above mentioned.

The crude distillate thus obtained contains some 2 to 5% water, which may be eliminated by settling it out in a settling tank.

We prefer not to treat the water-freed primary, crude distillate thus produced directly, in gross, but to separate it into a plurality of different portions by fractionation or reduction. The following examples (wherein the temperatures given are the vapor temperatures in the still, unless otherwise stated) will sufficiently illustrate the most convenient methods of redistillation:

(1) Condense separately the vapors coming from the still up to 475° F., and from 475° F., to 600° F.,—subsequently drawing off as residuum the oil unvaporized at the latter temperature, or allowing it to remain and mix with the next charge of crude oil.

(2) Condense separately the vapors up to 475° F.; from 475° F., to 650° F.; and from 650° F., until the temperature of the material in the bottom of the still is about 850° F. By this procedure, an amount of coke equal to about 2% of the crude oil charge will be produced.

In either of these cases, considerable destructive action occurs in the production of the higher fractions,—especially the last.

(3) Three fractions nearly similar to those described under (2) may be obtained at temperatures some 100° F., lower than those mentioned by carrying out the redistillation as described in U. S. Patent No. 877,620, granted January 28, 1908, to Wells, blowing carbon dioxide or other inert permanent gas through the liquid in the still. In this case, the destructive action is much less. It is advantageous to pass the gas and vapor coming off through a filter of fuller's earth in the dome of the still, on its way to the

condenser. A residuum of heavy oil will preferably be left in the still, as described under (1).

The gas from the primary distillation contains ammonia, which can be segregated as ammonium sulphate by a sulphuric scrubbing operation. The coke from both distillations also has a nitrogenous content recoverable by a similar operation in connection with conversion thereof into fuel gas by incomplete combustion in a by-product gas-producer. The water eliminated from the crude distillate also contains ammonia in solution, which may, if desired be also converted into ammonium sulphate. For these operations for recovery of ammonia may be used the unconsumed portion of the sulphuric reagent employed in the purification and sulphonation treatments hereinafter described.

Of the distillates thus produced, we generally prefer to treat the intermediate one. Prior to sulphonation treatment, however, we prefer to subject the gilsonitic material to preliminary purifying treatment with a sulphuric reagent, thus removing therefrom organic bases, olefines, and other impurities that might alter or impair the character and utility of the final products. This preliminary sulphuric treatment may be carried out by agitation of the gilsonitic material with about 5% of sulphuric acid of oil of vitriol grade,—i. e., about 66° Bé.,—for about one half hour. It is desirable to repeat the operation (using fresh acid) one or more times.

After this preliminary step, "sulphonation" treatment may be carried out by subjecting the purified gilsonitic oil to the action of a sulphonating reagent. The sulphonating reagents which we prefer to use are oil of vitriol, such as mentioned above, and fuming sulphuric acid or "oleum." It is desirable to conduct this treatment in a cast iron vessel, using mechanical agitation rather than air agitation in order to avoid such contamination with atmospheric moisture as might interfere with the desired reaction.

We have found that the quality of certain products ultimately obtainable is improved by carrying out this treatment progressively, with successive portions of reagent, and segregating the reaction products, as formed, from the material being treated, so that each of the successively acting portions of reagent shall be perfectly fresh and untainted with such reaction products. Further improvement can be obtained by starting with relatively weak reagent, and using more and more reactive or energetic reagent as the treatment progresses. This may be done in a succession of separate operations upon a single lot of material with different portions of reagent, rather than in

one single operation—say four such treatments, each with an amount of reagent equal to 20% of the material treated. Thus for the first treatment, the reagent may be oil 5 of vitriol alone; for the second, a mixture of 15 parts oil of vitriol and 5 parts oleum; for the third, a mixture of oil of vitriol and oleum in equal parts; for the fourth a mixture of 5 parts oil of vitriol and 15 parts 10 oleum. Each of these treatments may last about two hours.

If, on the other hand, it is desired to carry out sulphonation treatment all at once, in a single operation, rather than progressively, 15 it may be done by mechanical agitation for some eight hours,—using, say, an amount of sulphonating reagent equal to 80% of the material treated and consisting of 50 parts oil of vitriol and 30 parts oleum.

20 At the end of each treatment or operation, the charge in the agitator is allowed to stand an hour or more, when it will be found to have separated into two distinct layers: a top layer of residual or mother oil, and a 25 bottom layer of acid sludge. This latter should be drawn off and thus segregated prior to the next treatment of the mother material.

The residual oil remaining after the last 30 treatment has with water alone a strong emulsifying tendency; but it may nevertheless be washed with alcohol diluted with (say) an equal or double amount of water without any great difficulty. The oil may 35 then be neutralized, as with sodium hydroxide solution (preferably of specific gravity greater than 30° Bé., in order to insure against emulsification troubles). After the excess of caustic has been drawn off, 40 the resultant alkaline oil may be washed with water (without trouble from excessive emulsification) to remove any remaining excess of alkali. It may also be distilled with steam, in order to improve its color, and 45 even filtered through fuller's earth.

The organic material dissolved or extracted from the residual oil by the alcohol appears to be the cause of the emulsifying 50 property of the oil; for when recovered (by distillation of the alcohol), it itself presents this same property. As thus obtained, this extract derivative is an acid substance, brown to black in color, and with slight odor.

55 It has, in general, the useful properties of sulphonic acids. In appropriate combinations, therefore, its characteristic radical or radicals constitute a useful agent for many different purposes,—acting as hydrolyzer or saponifier for oils, fats, and other glycerides or fatty substances when employed in the usual manner, and have excellent detergent and emulsifying properties.

60 We have no proof, however, that it is 65 a true sulphonic substance or sulphonation

product, or that its characteristic radical is sulphonic. For hydrolyzing purposes, the agent in free acid form may be used; while for detergent or emulsifying purposes, the salt form will ordinarily be preferred. 70

As to the general properties of these gilsonitic derivative sulphonic materials, it is to be observed that the alkali salts (i. e., both ammonium and alkali metal salts) are water-soluble, as well as the acid; while 75 the alkaline earth and the other metal salts generally are water-insoluble. (These properties, it will be seen, specially adapt these materials to certain modes of use hereinafter described.) Both the acid and salt 80 forms are soluble in most organic solvents,—such as benzole, alcohol, petroleum naphtha, or other distillates,—and both salt and acid forms are more freely soluble in such solvents than in water. The dissolution of 85 the acid material in water is peculiar (probably owing to impurity), in that as water is gradually added to the material, it first gelatinizes and then goes more freely into solution. This general solubility in organic 90 solvents sharply distinguishes this gilsonitic sulphonic agent (derived by extraction from the sulphonation residual oil) from a somewhat similar gilsonitic sulphonic agent, obtainable from the sulphonation sludge by 95 dilution of the latter with an equal amount of water (with suitable precautions against over-heating) and allowing the dilute sludge to stand and settle some twelve hours, and then drawing off and purifying (by neutralization) the next to the bottom layer thus segregated. In practice, it is most convenient and desirable to handle, pack, and ship an agent of this sort in the form of 100 a dry, solid, stable salt, rather than in its more active free acid form. For detergent and emulsifying purposes, the sodium salt will ordinarily be preferable, on account of its relatively low cost. For saponifying or 105 hydrolyzing purposes, however, it is peculiarly advantageous to employ as the commercial material a salt with a volatile base, and to produce the active, free acid saponifier therefrom by acidulation when it is to be used,—either before or in the actual 110 treatment of the glycerides,—on account of the facility thus afforded for securing glycerine water free from saponifier, acidulent or other deleterious impurity. For this 115 purpose, the ammonium salt form of the agent is especially suitable. When this is used, the glycerine water subsequently obtained will contain only acid saponifier, acidulent, (usually sulphuric acid), and ammonium salt of the acidulent.

By addition to this glycerine water of a suitable base or salt (such as calcium hydrate or barium carbonate), insoluble salts of the acidulent and the saponifier will be formed and precipitated. This will leave in solution in the 120 125 130

glycerine water, as an impurity, only an unstable combination (ammonium hydroxide or carbonate) whose components can be volatilized and driven off by boiling.

5 Hereinbefore and in our claims, we have spoken of suphonating reagents, supphonation treatment, and sulphonation or sulphonic products, etc., using these expressions in reference to the chemical character and 10 mode of use of the reagent employed in the principal treatment described above, or to the useful properties of products resulting therefrom. As already stated, however, we do not mean by this language that our sulphonic products are true sulphonic substances in the sense of having sulphonic radicals,—since we are without clear evidence on this point.

Having thus described our invention, we 20 claim:

1. An extract derivative of gilsonitic sulphonation residual oil; having, in general, the useful properties of true sulphonic sub-

stances; and characterized by a radical whose alkali salts and free acid are soluble 25 in water, but whose alkaline earth salts are water-insoluble.

2. A gilsonitic sulphonation product, having, in general, the useful properties of true sulphonic substances; serviceable as an agent 30 for the hydrolysis of glycerides; detergent; and characterized by a radical whose alkali salts and free acid are water-soluble, and also soluble in organic solvents generally, but whose alkaline earth salts are water-in- 35 soluble.

In testimony whereof, we have hereunto signed our names at Maurer, N. J., this 29th day of March, 1922.
